CONTROLLER FOR ELECTRIC MOTOR
DRIVEN APPARATUS

Arthur T. Calvert, Manhasset, N. Y., assignor to
Cutler-Hammer, Inc., Milwaukee, Wis., a corporation of Delaware

Application September 20, 1951, Serial No. 247,478

7 Claims. (Cl. 318—210)

1

This invention relates to improvements in controllers for electric motor driven apparatus.

Controllers embodying the invention are especially advantageous for control of printing presses but are not limited to such application.

An object is to provide a controller of the class described which affords plugging of the motor after a relatively long forward inch but no plugging after a relatively short forward inch.

Another object is to provide a controller of the class described which provides high starting torque for regular operation and for forward and reverse inching.

A more specific object is to provide a controller of the class described which uses a time delay mechanism to determine whether the motor is to be plugged following forward inching.

Another object is to provide a controller of the class described which starts forward inching and running at high torque and also plugs at high torque, and

Another object is to provide a controller of the class described which after forward high torque inching changes the motor to approximately half running speed as governed by the aforementioned time delay mechanism.

Other objects and advantages of the invention will hereinafter appear.

The accompanying drawing illustrates one embodiment of the invention which will now be described, it being understood that the embodiment illustrated is susceptible of various modifications without departing from the scope of the appended claims.

In the drawing, the figure shows schematically and diagrammatically a preferred embodiment of the invention.

Referring to the drawing, the same shows a polyphase slip ring induction motor M having its primary P supplied from lines L¹, L² and L³ through conventional reversing switches F and R, each being of the triple pole electromagnetically operated type. The secondary S of the motor M has for its circuit delta connected speed regulating resistors r¹, r² and r³, as will later appear are adjustable through the medium of sliders 1, 2 and 3 which bridge different points of said resistors with segments 4, 5 and 6 respectively. These delta connected resistors are arranged in a well known manner as shown in the drawing. Point 25, which is the junction of resistors r¹ and r², is connected to a secondary terminal S³ while point 26, the junction between resistors r¹ and r³, is connected directly to secondary terminal S². The junction between resistors r² and r³, or point 27,

2

is connected to the secondary terminal S¹ through winding 13 of a plugging relay PR to be herein-after fully explained. Also the speed regulating resistors are provided with electroresponsive control switches 1A and T. These electroresponsive switches are of the triple pole type and provide for control for all of the speed regulating resistors in a given manner. As shown, switch T affords, by normally open contacts 23^a, 23^b and 23^c thereof, connections to taps 7, 8 and 9 of resistors r¹, r² and r³, respectively, and switch 1A provides through normally open contacts 24^c, 24^b and 24^a thereof connections to segments 4, 5 and 6 respectively. All of the contacts of switches 1A and T effect shorting-out of certain predetermined portions of resistors r¹, r² and r³ whenever their respective actuating windings are energized.

The drawing also shows a plugging relay PR depicted as comprising a double ended arm 10 movable to bridge either of two pairs of stationary contacts 11^a and 11^b. The relay has for moving its arm 10 into the position shown in full lines a winding 12 to be connected across lines L¹ and L² through contacts 22^b and 22^c of the reversing switch R, such influence of said winding 12 being opposed by the influence of the above-mentioned winding 13 in the secondary circuit of the motor. Also the relay PR has a winding 14 adapted to move the arm 10 into the dotted line position, said arm when not subjected to the influence of one or another of windings 12 and 14 being adapted to remain in the position to which it was last moved.

Connected to line L¹ through a normally closed momentary open stop button 15, is one side of the normally open momentary closed start button 16. The other side of said start button 16 is connected thru the coil 17 of electromagnetic switch CR and the normally closed contacts 22^d of the electromagnetic reversing switch R to line L². In parallel circuit arrangement with start button 16 are normally open contacts 17^b of the electromagnetic switch CR, said contacts 17^b providing a maintaining circuit when said start button is released. Connected between a point common to the left hand contact of start button 16, the right hand contact of stop button 15, the left hand contact of contacts 17^b and the left hand contact of contacts 18^a of the momentary three position reversing switch 18 are normally open contacts 17^a and a normally open momentary closed inch button 19; said contacts 17^a and button 19 being connected in parallel circuit arrangement. The right hand contact of contacts 18^a is connected to a point common to a lead wire

of each of the coils 20 and 21 of the electromagnetic switches F and TR respectively. The other lead wires of coils 20 and 21 are each connected to a point common to the coil 17 and the right hand contact of the normally closed contacts 22^d.

The above-mentioned reversing button 18 is also composed of three lower contacts 18^b, all of which are simultaneously bridged when the button 18 is held in its lowermost position. The left hand one of said contacts 18^b is connected to a point common to the left hand contact of contacts 18^a of said button 18, the left hand contact of inch button 19 and the right hand contact of contacts 17^a. The center contact of contacts 18^b is connected to a point common to the right hand contact of inch button 19, the left hand contacts of contacts 17^a and 17^b, the right hand contact of stop button 15 and the left hand contact of start button 16, while the right hand contact of contacts 18^b is connected to the line L² through the normally closed contacts 20^d and winding 22 of the electromagnetic switch R. The normally open contact 20^c of switch F is connected between line L¹ and a point common to the left hand contact of contacts 20^d and the right hand contact of contacts 18^b of the reversing button 18.

The electromagnetic switch TR is a timing relay consisting of a winding 21, normally open contacts 21^a, normally closed contacts 21^b and a timing mechanism represented by the dashpot 21^c. The normally closed contacts 21^b are connected from line L² through winding 23 of the electromagnetic switch T to a point common to the right hand contact of contacts 18^b and contacts 20^d and 20^e. The normally open contacts 21^a are connected from line L² through winding 24 of the electromagnetic switch T through the normally open contacts 17^c to a point common to winding 23, contacts 20^d and 20^e and the right hand contact of contacts 18^b. In series with each other but in electrical parallel with respect to winding 24 and contacts 17^c are winding 14 and contacts 11^a when arm 10 is in the full line position (as shown). When arm 10 is in the dotted line position, a circuit is completed from line L¹ through the stationary contacts 11^b and arm 10 to a point common to the right hand contacts of contacts 17^c, 18^b and 20^e.

The circuit operates as follows: Upon depressing the start button 16, current flows from line L¹ through buttons 15 and 16, winding 17 and normally closed contacts 22^d to line L². The energization of winding 17 closes contacts 17^a, 17^b and 17^c. The closing of contacts 17^a allows current to flow from line L¹ through button 15, contacts 17^a, contacts 18^a of switch 18 and thence in parallel through windings 20 and 21, and contacts 22^d to line L². The closing of contact 17^b provides a maintaining circuit for start button 16 so that when said button 16 is released, the starting circuit through winding 17 is maintained.

The energization of winding 20 affords current to the primary P of motor M through the closing of contacts 20^a, 20^b and 20^c. The closing of contacts 20^c provides current flow from line L¹ through contact 20^c, winding 23 and the then closed contacts 21^b to line L². Contacts 21^b initially remain closed even though winding 21 is energized, and are opened after a predetermined time delay as determined by the timing mechanism 21^c. Thus the motor M has started with contacts 23^a, 23^b and 23^c closed providing high starting torque as the result of shorting-out a certain portion of resistors r¹, r² and r³. As the motor M accelerates, and the timing mechanism

21^c has run a sufficient length of time to allow contacts 21^a to close and contacts 21^b to open, winding 23 is deenergized by said opening of contacts 21^b. Upon the closing of contact 21^a, a circuit is provided from line L¹ through contacts 20^c and 17^c, winding 24 and contact 21^a to line L². The motor secondary starting connections are disconnected by the deenergization of winding 23 while the operating speed connections are applied as the result of the closing of contacts 22^a, 22^b and 22^c. Also due to the closing of contacts 21^a is the current flow from line L¹ through contacts 20^c, stationary contacts 11^a and arm 10, winding 14 and contacts 21^a to line L². Upon energization of winding 14, the plunger 12^a is caused to move upwardly thereby swinging the arm 10 into the dotted line position. Movement of arm 10 into the last mentioned position affords deenergization of winding 14. The motor is thereby running at a forward operating speed according to the predetermined setting of the sliders 1, 2 and 3 on the resistors r¹, r² and r³ respectively.

If it is desired to stop the motor M, the stop button 15 is depressed. This opens various circuits which results in the deenergization of windings 17, 20 and 21. The deenergization of winding 20 causes the main contacts 20^a, 20^b and 20^c to open, effecting disconnection of motor primary P from the supply lines L¹, L² and L³. The contacts 20^d are closed by this deenergization thereby providing a circuit from line L¹ through the stationary contacts 11^b and arm 10 (in dotted line position), contacts 23^d and winding 22 to line L². The energization of winding 22 and the resultant closing of contacts 22^a, 22^b and 22^c, applies reverse power to the motor primary P in a well known manner. Also contacts 22^d are opened by winding 22 so that it is impossible for winding 20, 21 and 17 to be energized while the reverse winding 22 is in operation. Simultaneous with the application of reverse power to the motor primary P, is the closing of contacts 21^b and the opening of contacts 21^a, 17^a, 17^b and 17^c. The closing of contacts 21^b energizes winding 23 through the arm 10 (still in the dotted line position) so that high torque plugging is accomplished by the shorting-out of the above-mentioned portions of resistors r¹, r² and r³ when the contacts 23^a, 23^b and 23^c are closed. The opening of contacts 17^c disconnects winding 24 from the source of power.

The locking winding 13 of the PR relay has been the only winding of said relay which has remained energized since the plunger 12^a has caused arm 10 to assume the dotted line position. Said winding 13 remains energized whenever power, either forward or reverse, is applied to the motor secondary and effects plunger 12^a to try to keep it in its lowermost position or away from the arm 10. The energization of winding 22 also closes contacts 22^c which in turn provides for subjection of winding 12 to line voltage during the plugging operation. In the practical application of the invention, contacts 22^c are constructed to close shortly after the closing of contacts 22^a, 22^b and 22^c to insure the energization of the locking winding 13 before the energization of winding 12, so that at the start of the plugging operation, arm 10 will remain in the dotted line position.

As the motor is plugged and slows down, the motor secondary current decreases in accordance with the speed of said motor M. This decrease in secondary current results in a decrease in current flow through winding 13 until it reaches a prede-

terminated low value where the winding 12, having a constant current flow, dominates the plunger 12^a and causes it to move upwardly and return arm 10 to the heavy line position. This causes the deenergization of winding 22 resulting in the removal of electrical power from the motor and all of the circuit components. The motor then comes to rest, in a relatively few number of revolutions, due to friction.

If inching or jogging is required, it can be accomplished by depressing and releasing the inch button 19. This results in the same operations as when the start button 16 is pressed as above-described in detail, except that by pressing the inch button 19 the winding 17 is never energized thereby keeping winding 24 from ever being energized. Therefore, when the high starting torque winding 23 is deenergized by the opening of contacts 21^b, all of the resistance of resistors r¹, r² and r³ are in the secondary circuit allowing the motor to come up to approximately only half running speed, a condition which is very ideal during inching. When the contacts 21^a are closed the arm 10 is moved into the dotted line position thus providing a maintaining circuit for contacts 20^c when the inch button 19 is released, the result, of course, being plugging of the motor as above described. If the inch button 19 is not depressed long enough to allow contacts 21^a to close and contacts 21^b to open, arm 10 will remain in the heavy line position and no plugging will result when button 19 is released. The motor will then come to rest due to the inherent friction in the motor and the driven machine.

The reverse button 18 as above-mentioned is a three position switch. It is biased to normally bridge contacts 18^a but may be held in the lowermost position, where it bridges contacts 18^b or it may be held in the intermediate position which is represented by the dotted line between the sets of contacts. If said button 18 is depressed to its mid position (broken line) it functions the same as stop button 15. If the motor M is running in the forward direction and button 18 is depressed to bridge contacts 18^b and is then released, the same operation will result as is caused by depressing and releasing stop button 15. These functions above-mentioned are not the normal uses for button 18 since the stop button serves the same purpose. However, said button 18 is primarily used for reverse inching or jogging by bridging contacts 18^b of button 18 when the motor is at rest. A circuit is thereby completed from the line L¹, through stop button 15, the right hand and center contacts of contacts 18^b, closed contacts 20^d and winding 22 to line L². This applies reverse power to the motor M causing the motor to run in a reverse direction. Another circuit is completed through button 15 from line L¹, through the two right hand contacts of contacts 18^b, winding 23 and closed contacts 21^b to line L². Thus the motor is operated at high torque in the reverse direction. The windings 20, 21, 17, 24, 12, 13 and 16 are not energized on the reverse inch so that as long as the reverse button 18 is bridging contacts 18^b, the motor M will run in the reverse direction at high torque. When said button 18 is released the motor will come to rest due to the inherent friction of said motor and the driven machine.

I claim:

1. In a system for plugging an electric motor, comprising in combination, means including an electroresponsive switch for connecting said motor to a source of electrical energy for running,

a second electroresponsive switch energizable to connect said motor to a source of electrical energy for plugging, and control means for controlling connection of the operating winding of said second electroresponsive switch to its source comprising time delay means operable a predetermined time following energization of said first mentioned switch and switch means acting as a result of operation of said time delay means to effect energization of the operating winding of said second electroresponsive switch when the first mentioned electroresponsive switch is deenergized, said switch means having means responsive to motor slow-down during plugging to deenergize said second electroresponsive switch.

2. In a system for inching an electric motor, comprising in combination, means including an electroresponsive switch for connecting said motor to a source of electrical energy for inching, a second electroresponsive switch energizable to connect said motor to a source of electrical energy for plugging, and control means for controlling connection of the operating winding of said second electroresponsive switch to its source comprising a time delay relay having an operating winding energizable in response to operation of said first mentioned means and having normally open contacts, and a transfer switch having an electroresponsive winding energizable as a result of closure of said relay contacts to effect energization of the operating winding of said second electroresponsive switch when the first mentioned electroresponsive switch is deenergized, said transfer switch having means acting as a result of motor slow down during plugging to deenergize said second electroresponsive switch.

3. In a system for plugging an electric motor, in combination, a motor, a source of electrical power supply, means including an electroresponsive switch for connecting said motor to said source for running, a second electroresponsive switch energizable to connect said motor to said source for plugging, and control means for controlling connection of the operating winding of said second electroresponsive switch to said source comprising time delay means operable a predetermined time following energization of said first mentioned switch and switch means acting as a result of operation of said time delay means to effect energization of the operating winding of said second electroresponsive switch when the first-mentioned electroresponsive switch is deenergized, said switch means having means responsive to motor slow-down during plugging to deenergize said second electroresponsive switch.

4. In a system for inching an electric motor, in combination, a motor, a source of electrical power supply, means including an electroresponsive switch for connecting said motor to said source for inching, a second electroresponsive switch energizable to connect said motor to said source for plugging, and control means for controlling connection of the operating winding of said second electroresponsive switch to said source comprising a time delay relay having an operating winding energizable in response to operation of said first mentioned means and having normally open contacts and a transfer switch having an operating winding energizable as a result of closure of said relay contacts to effect energization of the operating winding of said second electroresponsive switch when the first mentioned electroresponsive switch is deenergized, said transfer switch having means acting as a result

of motor slow-down during plugging to deenergize said second electroresponsive switch.

5. In a system for inching an electric motor, in combination, a motor, a source of electrical power supply, means including an electroresponsive switch for connecting said motor to said source for inching, a second electroresponsive switch energizable to connect said motor to said source for plugging, and control means for controlling connection of the operating winding of said second electroresponsive switch to said source comprising a time delay relay having an energizing winding responsive to operation of said first mentioned means and having normally open contacts, and a transfer switch having a contactor and first, second and third operating windings, said first winding being energized as a result of closure of said relay contacts to operate said contactor from one position to another to afford energization of said second electroresponsive switch, said second winding being energized as a result of operation of said second electroresponsive switch and tending to operate said contactor to said one position, said third winding being energized as a function of motor speed and preventing operation of said contactor to said one position pending motor slow-down to a given speed during plugging.

6. In a system for inching an electric motor, comprising in combination, means including an electroresponsive switch for connecting said motor to a source of electrical energy for inching, a second electroresponsive switch energizable to connect said motor to a source of electrical energy for plugging, and control means for controlling connection of the operating winding of said second electroresponsive switch to said source comprising a time delay relay having an energizing winding responsive to operation of said first mentioned means and having normally open contacts and a transfer switch having first, sec-

ond and third electroresponsive windings and a contactor, said first winding being energizable as a result of closure of said relay contacts to effect energization of the operating winding of said second electroresponsive switch when the first mentioned electroresponsive switch is deenergized, said second and third windings being energizable with current from said source and the motor secondary respectively and producing opposing effects on said contactor during plugging to afford deenergization of said second electroresponsive switch when the energizing current of said third winding reaches a predetermined value during motor slow-down.

15. 7. In a system for plugging an electric motor, comprising in combination, means including an electroresponsive switch for connecting said motor to a source for running, a second electroresponsive switch energizable to connect said motor to a source of electrical energy for plugging, control means for controlling connection of the operating winding of said second electroresponsive switch to its source comprising time delay means operable a predetermined time following energization of said first mentioned switch, means including a third electroresponsive switch having an operating winding energizable to effect greater torque during plugging than during normal run of the motor, and switch means acting as a result of operation of said time delay means to effect energization of the operating windings of said second and third electroresponsive switches when said first mentioned electroresponsive switch is deenergized, said switch means having means responsive to motor slow-down during plugging to deenergize said second electroresponsive switch.
